(57) **CLAIM**

The ornamental design for a goose stuffed animal, as shown and described.

DESCRIPTION

FIG. 1 is a front, top perspective view of a goose stuffed animal, showing my new design;
FIG. 2 is a rear, bottom perspective view thereof;
FIG. 3 is a front elevational view thereof;
FIG. 4 is a rear elevational view thereof;
FIG. 5 is a left-side elevational view thereof;
FIG. 6 is a right-side elevational view thereof;
FIG. 7 is a top plan view thereof; and
FIG. 8 is a bottom plan view thereof; and,
FIG. 9 is an enlarged view of the area labeled 9 in FIG. 1. The evenly spaced broken lines immediately adjacent to the shaded areas depict the bounds of the claimed design, while all other evenly spaced broken lines are directed to environment, and the dot-dash-dot broken lines depict bounds of the enlarged view in FIG. 1 and FIG. 9. The broken lines form no part of the claimed design.
